UNITED STATES PATENT OFFICE.

JOSEPH L. STENGEL, OF MIDDLESBORO, KENTUCKY, ASSIGNOR TO MARTIN-PAGE COMPANY, OF MIDDLESBORO, KENTUCKY, A CORPORATION OF KENTUCKY.

METHOD OF FORMING ATHLETIC SUPPORTERS.

Application filed May 23, 1925. Serial No. 32,396.

To all whom it may concern:

Be it known that JOSEPH L. STENGEL, a citizen of the United States residing at Middlesboro, in the county of Bell and State of Kentucky, has invented certain new and useful Improvements in Methods of Forming Athletic Supporters, of which the following is a specification.

This invention relates to new and useful improvements in methods of forming athletic supporters generally, although from certain aspects the invention relates to methods of forming flat seams employed in various garments.

Athletic supporters as heretofore constructed have been formed with lapped seams which have necessitated one face only being positioned in direct contact with the wearer in order to avoid any chafing or rubbing which would otherwise occur should the reverse side of the supporter be placed in direct contact with the wearer. Furthermore, in supporters heretofore constructed elastic webbing has been employed, but the seams connecting the various sections of the webbing have not been constructed so as to retain the supporter in proper shape nor to prevent the cut ends of the sections from projecting through such seams.

One of the important objects of my invention is to provide a method of forming a supporter in which each of the seams thereof includes adjacent webbing sections disposed in edge abutting relation whereby the supporter may be readily reversed and either face thereof employed in direct contact with the wearer without any chafing or rubbing action resulting therefrom.

Another important object of the invention is to provide a method of joining two elastic web sections by a seam which is so constructed as to not only cover the severed ends of the webbing, but also anchor the rubber strands of the webbing whereby they will be retained in their normal positions whenever the webbing is subjected to longitudinal expansion.

Another object of the invention lies in a method of forming supporters which consists in forming a flat seam having a reinforcing tape secured along the cut edge portion of one of the webbing sections so as to prevent stretching of the webbing whereby said webbing will retain its original shape and whereby said tape will assume all strain

which would otherwise be directed to said webbing.

With these and other objects in view which will more readily appear as the nature of the invention is better understood, the same consists in the novel method herein-after more fully described, illustrated and claimed.

In the accompanying drawings,—

Figure 1 is a perspective view of an athletic supporter constructed in accordance with my improved method.

Figure 2 is a plan view showing the two blanks from which the pouch is formed.

Figure 3 is a similar view but showing the lower portions of the pouch sections after being trimmed and the cut edges covered by stitches which secure inelastic tapes along said edges.

Figure 4 is a view showing the pouch sections secured by a line of stitches which retain the meeting edges in abutting relation, and also showing the upper cut edges thereof covered by a line of covering stitches which also secure an inelastic tape along said cut edges.

Figure 5 is an enlarged detail view showing the seam connection between the pouch sections.

Figure 6 is a plan view of the webbing forming the side straps, the cut ends being covered by a line of stitches which also secure inelastic tapes along said cut edges.

Figure 7 is a detail bottom plan view showing the seam connection between the side straps and the pouch.

Figure 8 is a plan view of the blank which forms the waist band, the cut ends being covered by stitches which also secure inelastic tapes along said cut edges.

Figure 9 is an enlarged detail view showing the seam construction which connects the pouch and the belt.

Figure 10 is a diagrammatic view of the seam connecting the pouch and side straps.

Figure 11 is a diagrammatic view showing a modified form of seam.

Figure 12 is a diagrammatic view showing another modified form of seam.

Figure 13 is a diagrammatic view of the seam connection between the pouch sections.

Figure 14 is a diagrammatic view showing the seam connection between the ends of the waist band.

Figure 15 is a diagrammatic view show-

ing the seam connection between the waist band and one of the straps, and

Figure 16 is a diagrammatic view showing the seam connection between the waist band and the pouch.

Like reference numerals designate corresponding parts throughout the several figures of the drawings.

Referring to the accompanying drawings, 10 the athletic supporter which is made in accordance with my improved method is indicated as a whole by the reference letter A. This supporter is preferably formed throughout the elastic webbing sections and 15 includes a waist band B, a pouch C, and side straps D, D.

The webbing sections are each formed of woven cloth and include a plurality of rubber strands 5 which extend longitudinally 20 thereof, the longitudinal edges being selvages. Thus each section is capable of longitudinal expansion but incapable of transverse expansion. It will therefore be understood that if a section is cut across at any 25 angle less than 90 degrees, the cut edge is rendered capable of being expanded, and the smaller the degree of the cut the greater the amount of expansion can be obtained. It will also be understood that unless the 30 severed end portions of the rubber strands are properly anchored, any longitudinal expansion of a section will serve to pull said end portions of the strands towards the center of the section, i. e., away from the cut 35 edge of the section. The effect of this movement of the strands is to reduce the elastic efficiency of the section, to change the shape of the section, and to produce a wavy and therefore objectionable appearance to said 40 section.

In carrying out my method I preferably first construct the pouch C, then join the side straps to the pouch, then join the pouch to the waist band, then join the side straps 45 to the waist band, and finally close the ends of the waist band. The method employed in joining all of these parts is such as to produce flat seams in which the adjacent edges of the parts so seamed are disposed in 50 abutting relation. These seams, therefore, permit of the supporter being readily reversed and also prevent any chafing or rubbing action on the wearer regardless of 55 which face of the supporter is in direct contact with said wearer.

The pouch C is formed from two webbing sections 6, 6, the side straps D, D are preferably formed from a single elastic webbing section 7, and the belt B is preferably formed 60 from a single elastic webbing section 8.

The pouch sections 6, 6 are first cut from a webbing and each section is then fed through an overlock sewing machine which includes a stitch forming mechanism for 65 producing a line of over-edge stitches and a

trimming mechanism which is disposed in advance of the stitch forming mechanism for initially trimming the edge of the fabric prior to the covering thereof by said stitches. The lower portion of each section 70 is cut transversely by said trimming mechanism on a curved line 7 which extends from one longitudinal edge of the section to the other. Simultaneously with this cutting and stitch forming operation an inelastic tape 8 75 is secured along one face of said curved cut edge 7 by a line of covering stitches 9. These overlock or over-edge stitches include a needle thread 10 and a looper thread 11 as diagrammatically shown in Figure 13, the 80 needle thread including a plurality of penetrant needle thread loops 10^a. Between adjacent needle loops the needle thread is formed into covering loops 10^b which extend laterally beyond and cover the cut edges of 85 the section. The covering loops 10^b are concatenated along the cut edge with the covering loops 11^a formed by the looper thread 11, the looper thread loops being in turn concatenated with the needle thread loops on the 90 outer face of the section. The inelastic tape 8 is simultaneously secured along said cut edge by the covering stitches 9, the needle thread loops 10^a projecting through said 95 tape and pouch section 6. Thus the needle thread loops serve to anchor the rubber strands 5 of the webbing against bodily movement when the webbing is expanded longitudinally, and by reason of these needle thread loops and the looper thread loops extending over the cut edge of the section, the frayed ends of the woven cloth and the adjacent ends of the rubber strands are covered and are thereby held against working upwardly beyond the plane of either face of 100 the section. The two pouch sections 6, 6 are then placed side by side with their meeting edges arranged in abutting relation and the sections are then secured together by a line of zig-zag stitches 12. This line of zig-zag 105 stitches extends throughout the length of the pouch. These stitches include a needle thread 13 and a lower or looper thread 14, the needle thread being formed into a concatenated line of staggered needle thread 110 loops 15 which alternately penetrate both tapes 8 and both pouch sections 6, the stitches extending entirely along the tapes 8 and thence upwardly along the meeting edges of 115 the sections to the upper ends thereof. By thus curving the lower portions of the meeting edges of the pouch sections 6 and then joining said meeting edges by the line of zig-zag stitches 12, I have properly shaped the bottom portion of the pouch, and by employing the tapes 8 along said curved cut edges I have reinforced the same whereby the shape of the pouch will be maintained and whereby all strain will be imposed on 120 said tapes and consequently stretching of 125 said tapes and consequently stretching of 130

the sections lengthwise of the cut edges will be prevented.

The concatenated pouch sections 6, 6 are then fed through an overlock or over-edge 5 sewing machine of the type previously described and the upper cut edges of both sections are covered by a continuous line of covering stitches 16, said covering stitches being identical in construction with the covering 10 stitches 9 heretofore described. An inelastic tape 17 is simultaneously applied to one face of the pouch sections 6. This tape extends entirely across both sections, is positioned along the cut edges thereof, and is secured 15 to the sections by the line of stitches 16.

Thus by means of the stitches 9 and the 20 stitches 16, the opposite ends of the rubber strands 5 of both sections are anchored against bodily movement longitudinally. Therefore, when any longitudinal expansion 25 is directed to either or both pouch sections, the rubber strands will be securely retained against said bodily movement.

The side straps D, D are preferably formed 25 from the single blank or section of elastic webbing 7. The opposite ends of the blank are respectively fed through an overlock sewing machine of the type previously described and as a result an inelastic tape 18 is secured to each cut end by a line of covering 30 stitches 19, the stitches being of the same character as the stitches 9 previously described. The blank or section 7 is preferably folded intermediate its ends as shown in 35 Figures 7 and 10, and the folded edge portion is disposed in abutting relation to the lower or rear edge of the pouch C. The folded edge of the straps extend on opposite sides of the meeting edges of the pouch sections 6, 6, and while the parts are held in this position they are fed through a zig-zag 40 sewing machine whereby a line of zig-zag stitches 20 is caused to secure the side straps D, D to the pouch C. The zig-zag stitches 45 20 are of the same type as the zig-zag stitches 12 previously described.

The waist band B is preferably formed from a single blank or section of elastic webbing 8. The opposite ends of the blank are 50 respectively fed through an overlock sewing machine of the type previously described and as a result an inelastic tape 21 is secured to each cut end by a line of covering 55 stitches 22, the stitches being of the same character as the stitches 9 previously described.

The pouch C is then positioned with its upper covered edges arranged in abutting relation to the lower edge of the waist band B, and the parts while held in this relation are fed through a zig-zag sewing machine and are thereby joined by a line of zig-zag 60 stitches 23, said stitches being identical with the zig-zag stitches 12 previously described.

The upper ends of the side straps D are

then secured to the waist band B by separate although identical operations. The upper end of each strap is disposed in abutting relation to the lower edge of the waist band and the parts while in this relation are fed 70 through a zig-zag sewing machine which results in the parts being secured by a line of zig-zag stitches 24 which are identical in construction with the zig-zag stitches 12.

The waist band B is then closed, that is, 75 the cut ends are disposed in abutting relation and while retained in this position are fed through a zig-zag sewing machine which secures the parts in said abutted relation by a line of zig-zag stitches 25.

It is to be noted that wherever parts are joined by a line of zig-zag stitches, and an inelastic tape is employed in the connection, the needle thread loops pass through the tape 80 and the webbing section directly thereunder.

It may be desired to use other forms of covering stitches. In Figure 11 I have diagrammatically illustrated another form of covering stitches, and in this figure 26 indicates one fabric and 27 another fabric, the 85 edges being disposed in abutting relation. A tape 28 is secured to the fabric 26 by a line of triple interlock stitches which I have indicated as a whole by the reference numeral 29. These triple interlock stitches are produced by a triple interlock machine which includes three needles each carrying a thread, a threaded looper which cooperates with all three needles, and a cross stitch mechanism for laying one or more threads. 90 This seam shows a plurality of needle thread loops 30, 31 and 32, a looper thread 33 concatenated therewith, and one or more cross threads 34, the looper thread being disposed against the under face of the fabric and the cross thread or threads 34 being laid against the outer face of the tape. The left hand needle thread loops 30 extend along the cut 95 edge of the fabric 26.

In Figure 12 I have shown an overlock 100 covering stitch 35 which is the same as shown and described in connection with Figure 15, except that in this form I have employed a separate line of stitches 36 which may be either of the single thread or two thread 105 type. This line of stitches 36 includes needle thread loops which extend through the tape 37 and fabric 38 and tend to more firmly secure the ends of the elastic strands within the webbing.

Having thus described my invention what is claimed is:—

1. The method of forming a pouch for athletic supporters consisting in first cutting two sections from an elastic webbing, then cutting the lower portion of each section on a curve extending from one side edge of the section to the other and covering said cut edge with a line of covering stitches which engage and anchor the elastic 110

- parts of the webbing, then positioning said sections side by side with their edges abutting, and finally joining said sections along their meeting edges and their curved cut edges by a line of stitches. 5
2. The method of forming a pouch for athletic supporters consisting in first cutting two sections from an elastic webbing, then cutting the lower portion of each section on a curve extending from one side edge of the section to the other, simultaneously securing an inelastic tape along said cut edge by a line of stitches which cover said cut edge and engage and anchor the elastic parts of the webbing, then positioning said sections side by side with their edges abutting, and finally joining said sections along their meeting edges and their curved cut edges by a line of stitches. 10
3. The method of forming a pouch for athletic supporters consisting in first cutting two sections from an elastic webbing, then cutting the lower portion of each section on a curve extending from one side edge of the section to the other and covering said cut edge with a line of covering stitches which engage and anchor the elastic parts of the webbing, then positioning said sections side by side with their edges abutting, and finally joining said sections along their meeting edges and their curved cut edges by a line of zig-zag stitches including staggered needle thread loops alternately penetrating said sections. 15
4. The method of forming a pouch for athletic supporters consisting in first cutting two sections from an elastic webbing, then cutting the lower portion of each section on a curve extending from one side edge of the section to the other and covering said cut edge with a line of covering stitches which engage and anchor the elastic parts of the webbing, then positioning said sections side by side with their edges abutting, then joining said sections along their meeting edges and their curved cut edges by a line of stitches, and finally securing a single inelastic tape along the upper cut edges of the sections by a line of stitches. 20
5. The method of forming a pouch for athletic supporters consisting in first cutting two sections from an elastic webbing, then cutting the lower portion of each section on a curve extending from one side edge of the section to the other, simultaneously securing an inelastic tape along said cut edge by a line of stitches which cover said cut edge and engage and anchor the elastic parts of the webbing, then positioning said sections side by side with their edges abutting, then joining said sections along their meeting edges and their curved cut edges by a line of stitches, and finally securing a single inelastic tape along the upper cut edges of the sections by a line of stitches. 25
6. The method of forming an athletic supporter consisting in first forming a pouch by first cutting two sections from an elastic webbing, then cutting the lower portion of each section on a curve extending from one side edge of the section to the other and covering said cut edge with a line of covering stitches which engage and anchor the elastic parts of the webbing, then positioning said sections side by side with their edges abutting, then joining said sections along their meeting edges and their curved cut edges by a line of stitches, then positioning the upper edges of the pouch sections in abutting relation against the edge 70 of a waist band, and finally joining said pouch and band by stitches while in said abutting relation. 75
7. The method of forming an athletic supporter consisting in first forming a pouch by first cutting two sections from an elastic webbing, then cutting the lower portion of each section on a curve extending from one side edge of the section to the other, simultaneously securing an inelastic tape along 80 said cut edge by a line of stitches which cover said cut edge and engage and anchor the elastic parts of the webbing, then positioning said sections side by side with their edges abutting, then joining said sections along their meeting edges and their curved cut edges by a line of stitches, then covering both upper cut edges of both sections by a line of covering stitches, then positioning the upper edges of the pouch sections in 85 abutting relation against the edge of a waist band, and finally joining said pouch and band by stitches while in said abutting relation. 90
8. The method of forming an athletic supporter consisting in first forming a pouch by first cutting two sections from an elastic webbing, then cutting the lower portion of each section on a curve extending from one side edge of the section to the other, simultaneously securing an inelastic tape along 95 said cut edge by a line of stitches which cover said cut edge and engage and anchor the elastic parts of the webbing, then positioning said sections side by side with their edges abutting, then joining said sections along their meeting edges and their curved cut edges by a line of stitches, then covering both upper cut edges of both sections by a line of covering stitches, then positioning the upper edges of the pouch sections in 100 abutting relation against the edge of a waist band, and finally joining said pouch and band by stitches while in said abutting relation. 105
9. The method of forming a reversible athletic supporter from cut sections of elastic webbing comprising a pouch, a waist band and side straps, consisting in first forming the pouch, then abutting the upper 110 edges of the sections by a line of stitches. 115
- 120
- 125
- 130

- cut edge of the pouch to the lower edge of the waist band and joining the same by a seam, then abutting the cut edges of the side straps to the lower rear edge of the pouch 5 and joining the same by a seam, and then separately abutting the upper cut edges of the side straps and the lower edge of the waist band and joining the same by seams, said method including the formation of separate lines of stitches respectively extending transversely of certain of the sections adjacent the cut ends thereof for anchoring the elastic parts of said sections, said separate lines of anchoring stitches being formed 10 prior to the joining of the sections.
10. The method of forming a reversible supporter comprising a pouch, a waist band, and side straps, consisting in first forming the pouch by joining the abutting edges of two sections arranged side by side by a seam, 20 forming a line of stitches across the upper portion of the pouch adjacent the cut edges thereof for anchoring the elastic parts of the webbing sections, then abutting the upper edge of the pouch to the waist band and 25 joining the same by a seam, then forming separate lines of stitches respectively extending transversely of the side straps adjacent the cut ends thereof to anchor the elastic parts of said straps, then abutting 30 the side straps to the lower rear edge of the pouch and joining the same by a seam, and then separately abutting the upper edges of the side straps to the waist band and joining the same by seams. 35

In testimony whereof I hereunto affix my signature.

JOSEPH L. STENGEL.
